United States Patent Office

Des. 215,363
Patented Sept. 23, 1969

215,363

PHOTOGRAPHIC CAMERA OR SIMILAR ARTICLE

Peter T. Quinn, Brighton, N.Y., assignor to Eastman
Kodak Company, Rochester, N.Y., a corporation of New Jersey

Filed June 17, 1968, Ser. No. 12,387

Term of patent 14 years

Int. Cl. D16—01

U.S. Cl. D61—1

FIG. 1

FIG. 2

FIG. 3

FIG. 5

FIG. 1 is a front perspective view, taken from the upper-right corner, of a photographic camera or similar article, showing my novel design;

FIG. 2 is a front view thereof;

FIG. 3 is a rear perspective view thereof, taken from the lower-left corner; and

FIGS. 4 and 5 are, respectively, right and left end views thereof.

I claim:

The ornamental design for a photographic camera or similar article, as shown.
